Primary Examiner — Lucy Lieberman*(74) Attorney, Agent, or Firm* — Krieg DeVault LLP(57) CLAIM

The ornamental design for a watch dial, as shown and described.

DESCRIPTION

FIG. 1 is a front view of the watch dial of the present invention; and,

FIG. 2 is a front, right-side perspective view of the watch dial of FIG. 1.

The broken lines in the drawings are used to show portions of the watch dial that do not form part of the claimed design.
